US0D1045872S

(12) **United States Design Patent** (10) Patent No.: **US D1,045,872 S**
(45) Date of Patent: ** Oct. 8, 2024

(54) **BRACKET FOR PORTABLE DISPLAY DEVICE**

(71) Applicant: **LG DISPLAY CO., LTD.**, Seoul (KR)

(72) Inventors: **Sunghyun Heo**, Paju-si (KR); **Sangbum Lee**, Paju-si (KR); **Hongseok Seo**, Paju-si (KR); **Minkwan Seo**, Paju-si (KR)

(73) Assignee: **LG DISPLAY CO., LTD.**, Seoul (KR)

(**) Term: **15 Years**

(21) Appl. No.: **29/862,413**

(22) Filed: **Dec. 8, 2022**

(30) **Foreign Application Priority Data**

Jun. 9, 2022 (KR) 30-2022-0023021

(57) **CLAIM**

The ornamental design for a bracket for portable display device, as shown and described.

DESCRIPTION

FIG. 1 is a front, right, top perspective view of a bracket for portable display device showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is an exploded perspective view thereof.

The broken lines in the drawings depict portions of the bracket for portable display device that form no part of the claim.

1 Claim, 8 Drawing Sheets
